UNITED STATES PATENT OFFICE.

PETER THOMSEN, OF CASSEL-WILHELMSHÖHE, GERMANY, ASSIGNOR TO SCHMIDT'SCHE HEISSDAMPF-GESELLSCHAFT M. B. H., OF CASSEL-WILHELMSHÖHE, GERMANY, A CORPORATION OF GERMANY.

SUPERHEATER.

1,139,601.

Specification of Letters Patent. Patented May 18, 1915.

Application filed October 17, 1914. Serial No. 867,092.

To all whom it may concern:

Be it known that I, PETER THOMSEN, a subject of the King of Prussia, Emperor of Germany, and residing at Cassel-Wilhelmshöhe, Germany, have invented certain new and useful Improvements in Superheaters, of which the following is a specification.

My invention relates to superheaters especially applicable to fire tube boilers, having saturated steam headers situated above the fire-tubes, and superheated steam headers laterally disposed with respect thereto, and is more particularly applicable to locomotives. In known constructions of superheaters in which the distributing and collecting headers of the superheater are arranged in the smoke box above the fire tubes, steam pipes of comparatively large diameter lead from the collecting headers to the engine cylinders. Owing to the difference in expansion of these steam pipes and the boiler walls great stresses are introduced at the junction of the steam pipes with one another, and with the distributing and collecting headers, and also at the junction of the headers and the boiler's walls, so that leakage through failure of the joints is liable to take place at these points. Subsequent re-jointings at such points are generally difficult to accomplish owing to the obstructions in the smoke box. Further, as the headers are subjected both to the temperatures of saturated and superheated steam the unequal expansions resulting therefrom cause the material of which the headers are composed to be unduly strained. In known constructions of superheaters having saturated and superheated steam headers, situated laterally with respect to the fire tubes, the same disadvantages are generally present.

The object of my present invention is to render the interior of the smoke box more accessible than has hitherto been the case, and to construct a superheater in such a manner as to obviate the disadvantages arising from the differential expansion of the parts of the superheater and of the boiler which come in contact with superheated steam, saturated steam, and water respectively, the arrangement being such that the several superheater elements or rows of elements are easily accessible.

According to the present invention the saturated steam distributing header is ar-

ranged above the fire tubes, while on each side thereof a superheated steam collecting header is disposed. The superheater elements are arranged in vertical rows so that the ends of the rows of elements nearest to the superheated steam headers open into them at approximately the level of the lowest fire tubes provided with superheater tubes, while the ends of the rows of elements situated more remote open into the headers at lower levels, the arrangement being such that, viewed from the smoke box door, no single row of elements is obscured by another row. Each row of elements is, in the present construction entirely independent of the other rows, which is of great importance in erecting and also when it becomes necessary to replace damaged elements. This feature is of considerable practical importance, as in superheaters in which the saturated steam header is arranged above and the superheated steam headers are arranged at both sides of the fire box the ends of the superheater elements cross one another, and the removal of some of the elements necessitates the withdrawal of the elements which are situated in front of them.

A further advantage arising from the use of my invention resides in the fact that the junction of the superheater tubes and the headers is visible and easily accessible, while the risk of leakage at such junctions is reduced to a minimum, owing to the elasticity of the superheater elements arising from the length of bends with which they are provided. In superheaters constructed according to my invention, it can be easily attained that the saturated steam distributing header as well as the superheated steam collecting header or headers are situated substantially outside the smoke box. For instance, by utilizing the front tube plate of the boiler the saturated steam header may be accommodated in the steam space of the boiler, and the superheated steam header or headers may be accommodated in suitable apertures in the smoke box wall so that they are situated wholly or partly outside the smoke box.

In this arrangement junctions of large and rigid pipes are entirely obviated in the smoke box.

Referring now to the accompanying drawings which illustrate my invention: Figure 110

1 is a vertical cross-sectional elevation through the smoke box of a locomotive boiler provided with a superheater constructed according to my invention, the view being 5 taken from the smoke box door; Fig. 2 is a longitudinal section on the line 2—2 of Fig. 1; Figs. 3 and 4 are corresponding views of a modification.

In carrying the invention into effect according to one form, a header *c* is arranged in the smoke box *a*, horizontally above the fire tubes and in front of the tube plate *b*, the header being adapted to receive saturated steam from the boiler. The fire tubes 10 *e* in which the superheater elements *d* are disposed are arranged in seven vertical rows, each of which contains three fire tubes. In the lower half of the smoke box two superheated steam collecting headers *f* are arranged, in which the superheated steam coming from the superheater elements is collected, and from which it is conveyed to the cylinders of the engine. The collecting 15 headers are arranged vertically and their lower halves which project through the smoke box are provided with flanges, *g*, to which the steam pipes leading to the engine cylinders are connected. The collecting headers are also provided with flanges *h* to 20 which a pipe interconnecting the headers may be bolted. By means of this interconnection the steam of the entire superheater system is led to each cylinder, and the area of the steam superheating surface may be 25 made relatively small.

The ends of the superheater elements *d* projecting from the fire tubes *e* are bent toward the steam headers in such a manner that the ends of each vertical row of elements receiving saturated steam are situated in a vertical plane. The ends of the elements receiving the saturated steam open into an intermediate steam chest *k* which is 30 itself detachably connected to the saturated steam header. The ends of the elements which lead the superheated steam to the superheated steam headers are arranged in a horizontal plane, and are expanded into a common flange *j* by means of which they are attached to the superheated steam header. 35

The ends of those vertical rows of elements conveying superheated steam which are situated nearest the superheated steam headers are situated approximately on a level with the lowest fire tubes, while similar ends of those rows of elements which are situated more remote are arranged in succession at lower levels. In this arrangement each single vertical row of elements can be withdrawn separately without affecting the others, while the fire tubes, the superheater elements and the joints of both are easily accessible. Further, the superheater elements have great elasticity owing to the 40

length of bends with which they are provided. The arrangement is such that it is not possible for water pockets to be formed in the superheater elements.

The example of my invention shown in Figs. 3 and 4 differs from that above described in that the header receiving the saturated steam, instead of being situated in the smoke box, is arranged in the steam space of the boiler. The header is made of 75 steel, the shell of the boiler and the tube plate being utilized in its construction. The saturated steam is led to this header through a pipe (not shown) connected to the flange *m*. The ends of the superheater elements which receive the saturated steam are formed with a double bend, and are brought up horizontally to the tube plate. Each opens separately and directly into the steam header, as do also the ends of the 80 superheater elements which convey the superheated steam. Each element of a row can be removed singly, the top row being first removed, then the middle row and lastly the bottom row. Both ends of each 85 tube are attached by means of a common flange *i* and a screw to the respective steam header. The superheated steam headers, which in the example shown are situated partly inside and partly outside the smoke box, may also be arranged so as to be situated entirely outside. This latter arrangement renders the interior of the smoke box 90 more accessible and may be adopted with advantage in cases where space is limited. 100 In those cases in which the smoke box is large, the headers may be arranged entirely inside. Instead of attaching the ends of the superheater elements conveying superheated steam, to the superheater steam headers 105 from which the superheated steam is afterward led to the slide valve chests of the engine, the ends of the superheater elements may be attached directly to the valve chests, without departing from the scope of my invention. In such a case the ends of the superheater elements pass through the smoke box wall which is provided with suitable packing arrangements at these points 110 for the purpose of preventing the entrance 115 of air into the smoke box.

Having now particularly described and ascertained the nature of my said invention and in what manner the same is to be performed, I claim:

1. A steam superheater for fire tube boilers consisting of a saturated steam header located above the fire tubes, superheated steam headers disposed laterally thereto, and of superheater elements adapted to be inserted into the upper horizontal fire tube rows, and arranged in vertical rows, the elements of each vertical row terminating in the superheated steam header in such a way that the ends of the elements of the row 120

nearest to the superheated steam header open into them at the same level with the lowest fire tube row containing superheating elements while the rows of elements 5 more remote open at lower levels.

2. A steam superheater for fire tube boilers in combination with the usual tube sheet, consisting of a saturated steam header located above the fire tubes and extending 10 across said tube sheet, of superheated steam headers disposed on both sides of the tube sheet and of superheater elements adapted to be inserted into the upper horizontal fire tube rows, and arranged in vertical rows the elements of each vertical row terminating in the superheated steam header in such a way that the ends of the elements of the row nearest to the superheated steam header open into them at the 15 same level with the lowest fire tube row containing superheating elements while the rows of elements more remote open at lower levels.

3. A steam superheater for fire tube boilers in combination with the usual tube sheet, consisting of a saturated steam header located above the fire tubes and extending across said tube sheet, of superheated steam headers arranged on both ends of the 20 saturated steam header, perpendicularly thereto but spaced apart therefrom, each of said superheated steam headers provided with a face perpendicular to the tube sheet and of superheater elements in the upper 25 horizontal fire tube rows arranged in vertical rows, the elements of each vertical row terminating in said faces in such a way that the ends of the elements of the row nearest to the superheated steam header open into them at the same level with the lowest fire tube row containing superheating elements 30 while the rows of elements more remote open at lower levels.

4. A steam superheater for fire tube boilers parts of which are adapted to be inserted into the smoke box in front of the tube sheet, consisting of a saturated steam header located above the fire tubes and extending across the smoke box, of superheated steam headers arranged on both ends of the saturated steam header spaced apart therefrom, partly located inside and partly outside the smoke box, each of the superheated steam headers provided with a face 45 perpendicular to the tube sheet and of superheater elements adapted to be inserted into the upper horizontal fire tube rows and arranged in vertical rows the elements of each vertical row terminating in the superheated steam header in such a way that the ends of the elements of the row nearest to the superheated steam header open into them at the same level with the lowest fire tube row containing superheating elements 50 while the rows of elements more remote open at lower levels.

60

while the rows of elements more remote 65 open at lower levels.

5. A steam superheater for fire tube boilers parts of which are adapted to be inserted into the smoke box in front of the tube sheet, consisting of a header for saturated steam located in the steam space of the boiler, of superheated steam headers on each side of the smoke box, provided with a face perpendicular to the tube sheet and of superheater elements adapted to be inserted 70 into the upper horizontal fire tube rows and arranged in vertical rows the elements of each vertical row terminating in the superheated steam header in such a way that the ends of the elements of the row nearest to the superheated steam header open into them at the same level with the lowest fire tube row containing superheating elements 75 while the rows of elements more remote open at lower levels.

6. A steam superheater for fire tube boilers consisting of a header for saturated steam, of superheated steam headers arranged on both ends of the first-named header but spaced apart therefrom, of superheating elements adapted to be inserted into the upper horizontal fire tube rows and arranged in vertical rows, the elements of each vertical row terminating in the superheated steam header in the same order as in 90 the saturated steam header, in such a way that the ends of the elements of the row nearest to the superheated steam header open into them at the same level with the lowest fire tube row containing superheating elements 95 while the rows of the more remote elements open at lower levels.

7. A steam header for fire tube boilers provided with a smoke box, consisting of a header for saturated steam located in the steam space of the boiler, of superheated steam headers on both sides of the smoke box extending partly outside thereof, and of superheating elements adapted to be inserted in the upper horizontal fire tube rows 100 and arranged in vertical rows, all the elements belonging to one superheated steam header bent to enter their respective fire tubes on the same side and leaving it at the other side, the elements of each vertical row terminating in the superheated steam header in the same order as in the saturated steam header, in such a way that the ends of the elements of the row nearest the superheated steam header open into them at 105 the same level with the lowest fire tube row containing superheating elements while the rows of the more remote elements open at 110 lower levels.

8. A steam superheater for fire tube 115 boilers consisting of a saturated steam header located above the fire tubes, superheated steam headers disposed laterally 120

thereto, of superheater elements adapted to be inserted into the upper horizontal fire tube rows and arranged in vertical rows the elements of each vertical row terminating in the superheated steam header in such a way that the ends of the elements of the row nearest the superheated steam header open into them at the same level with the lowest fire tube row containing superheating elements while the rows of elements more re-

mote open at lower levels, and of flanges adapted to connect all the elements of a vertical row to the superheated steam header.

In testimony whereof, I have hereunto set my hand in the presence of two subscribing 15 witnesses.

PETER THOMSEN.
